(57) **CLAIM**

The ornamental design for an upper-limb detecting device as shown and described.

DESCRIPTION

FIG. 1 is a top, front and left side perspective view of an upper-limb detecting device showing our new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof; and,
FIG. 7 is a bottom plan view thereof.
